UNITED STATES PATENT OFFICE.

DAVID H. BELLAMORE, OF NEW YORK, N. Y., ASSIGNOR TO THE MOSLER SAFE COMPANY, OF HAMILTON, OHIO, A CORPORATION OF NEW YORK.

METALLIC STRUCTURE.

Application filed July 14, 1923. Serial No. 651,468.

My invention relates to metallic structures, such as safes, safe cabinets and the like, having door jamb walls and doors. This invention relates particularly to the jamb portions and to the door edge portions of such a structure.

The objects of my invention include the provision of a structure of the character referred to so designed and constructed at the 10 jamb and door edge portions thereof that the travel of heat into the interior of the structure is obstructed, retarded and prevented along or through either one or both of said portions, and particularly through 15 the jamb walls, the door edge walls, the joints between said walls and along a course or path behind either of the said walls.

A further object of my invention is to provide a construction of jamb and door 20 edge walls which permits expansion of said walls and adjacent portions of the structure without harmful effects upon the construction as the result of such expansion, and to provide a construction which, in consequence 25 of such expansion under the influence of heat, effects a more positive sealing of the joint between the jamb and door edge walls, and thereby enhances the action of the means which retard heat travel through 30 said joint.

Other objects of this invention will be in part obvious and in part pointed out hereinafter.

In accordance with my invention I perforate the jamb walls and the door edge walls in such a way that each of said walls comprises two or more portions which are substantially out of heat-conducting contact with each other except at very small connecting portions which are present between adjacent apertures, the apertures being comparatively large. These apertures are provided preferably in one or more continuous lines which extend entirely about the jamb 35 and door edge walls, and serve to decrease the amount of heat-conducting contact between the portions of the walls divided thereby, and to retard and diminish considerably the conduction of heat from one wall 40 portion to another. It is also believed that when one of said portions of a wall has become heated to such an extent that it expands, the small metallic portions which bridge the two portions will expand also 45 and will stretch, with the result that the adjacent portion of the wall will remain in place and will be uninfluenced by the distortion of the distorted portion. In order to retard and obstruct the travel of heat through the joint between the jamb walls 60 and the door edge walls, strips or cords, or the like, of insulating material may be disposed on either or both the jamb walls and the door edge walls, which may conveniently be accomplished by lacing said material alternately in and out of one or more lines of perforations. Each line of such insulating material is adapted to be contacted either by the wall of the other (jamb or door) member or by a similar line of non-conducting 65 material carried thereby. When a filling is present in a structure of this type, such filling is apt to crack or shrink away from the jamb walls and from the door edge walls under the influence of intense heat, thus 70 leaving passages or chambers directly behind these walls along or through which heat is apt to travel toward the interior of the structure. In order to obstruct and retard the travel of heat along such paths, 75 I provide on the jamb and door edge walls metallic projections which extend sidewise into the filling material and serve to absorb heat traveling behind the walls, and which serve to diffuse and to radiate such heat into 80 the filling material for absorption thereby. These radiating flanges also act to retard the heat travel directly through the walls by conducting and diffusing heat therefrom 85 into the filling material. In addition to the 90 above I preferably provide also a bolt-engaging jamb plate which is insulated from both the jamb wall and the inner wall of the structure, and which has a forwardly extending projection which is adapted to be 95 contacted by insulating material carried on the inner wall of the door to effect a tight seal between the door and the body of the structure at such point. Such insulating material on the door is interposed preferably 100 between the wall edge and the rear wall of the door to prevent and retard heat conduction from the door wall to the door rear wall. The seals above referred to retard the 105 passage of heat from the space between the bolt-plate on the jamb and the door edge wall into the interior of the structure. Moreover, when, as by means of opposed insulating material carried on the jamb walls 110 and door edge walls, there is provided a seal

which closes the joint between the door and jamb walls, an insulating dead air chamber will be produced between such seal and the seal at the rear wall of the door.

5 In order that a clearer understanding of this invention may be had, attention is hereby directed to the accompanying drawings, forming a part of this application and illustrating certain possible embodiments of my 10 invention.

Referring to the drawings, Fig. 1 is a fragmentary sectional view of a metallic structure embodying my invention; Fig. 2 is a perspective view of a fragment of an 15 edge of the door of said structure; Fig. 3 is a perspective view of a fragment of the jamb portion of such structure; Fig. 4 is a fragmentary sectional view taken on the line 4—4 of Fig. 1; Fig. 5 is a fragmentary sectional view of a modified form of 20 jamb and door edge wall construction; Fig. 6 is a fragmentary sectional view of another modification of the jamb wall and door edge wall; Fig. 7 is a fragmentary sectional view 25 taken on the line 7—7 of Fig. 6; and Fig. 8 is a fragmentary sectional view of still another modified jamb and door construction. Similar reference characters refer to 30 similar parts throughout the several views of the drawings.

Referring to the drawings, the structure includes a body member having a doorway and jamb, and a door having edge walls adapted to seat in said jamb. The said 35 body portion includes outer walls, such as 1, and inner walls, such as 2, and jamb walls such as 3. The door comprises outer wall 4, inner wall 5, and edge walls, such as 6. Jamb wall 3 and door edge wall 6 are of 40 conventional step formation, except that each is provided with two lines of heat-retarding perforations or apertures, also with metallic tongues extending sidewise from the walls into the conventional filling material 7 provided in the body portion and in 45 the door portion, and are provided with joint-sealing, insulating material, all as will now be particularly described.

As shown, the door edge wall 6 is provided with an outer line of apertures 8 and with an inner line of apertures 9, said lines of apertures being spaced from each other and in effect, divide the jamb wall 3 into three portions: an outer portion 10, a median 50 portion 11, and an inner portion 12. Portions 10 and 11 are out of heat conducting contact with each other except for the small metallic portions 13 which are present between adjacent apertures 8, and portions 11 and 12 are out of heat conducting contact 55 with each other except for similar small metallic portions 14 which are present between adjacent apertures 9. At the rear of the door a conventional chamber 15 may be 60 provided for bolt work, one of the bolts be-

ing diagrammatically represented at 16. The bolts are adapted to slide back and forth through suitable perforations or apertures in the portion 17 of the door edge. The edge of rear wall 5 of the door is flanged toward the front and is there parallel with the inner edge of wall portion 17. A strip of insulating material 18 is firmly secured between said portions of members 5 and 17, and serves to retard or prevent the conduction and travel of heat from the portion 17 to the rear door wall 5. Extending sideways from the inner surface of door edge wall 6 are metallic tongues or projections 19 which enter substantially within the filling 7 of the door and serve to diffuse and radiate heat thereto, thus retarding the travel of heat through the door wall 6 or along a path behind said wall. These projections or tongues 19 may readily be formed by stamping out the apertures 8 and 9 in such a way that the removed metal is bent sideways of the wall 6, forming the apertures and projections in the one operation. However, if desired, such radiating tongues may be provided in other ways, as by securing separate angle-shaped members, such as 19' (Fig. 8), to the jam and door edge walls, as by welding or by other suitable means. Members 19' may be continuous or interrupted, as desired, and may be employed either without perforations or lacings in the walls or in combination therewith.

The jamb walls 3 are of a construction similar to the construction of door edge wall 6, in that the jamb walls have an outer line of apertures 20, an inner line of apertures 21, and radiating tongues or projections 22 extending sideways from the rear of the jamb wall into the filling material 7. The jamb wall is thus divided into three portions: outer portion 23, median portion 24, and inner portion 25, each portion being separated from the adjacent portion by a line of perforations and being out of heat-conducting contact with each other except for the small portions of metal, such as 26 and 27, which remain between adjacent apertures 20 and 21 of each line. At the inner portion of the jamb wall is a bolt-receiving plate 28 separated from the portion 25 of the jamb wall by a strip of suitable insulating material 29, whereby said portions 25 and 28 are kept out of heat conducting contact with each other, and whereby the travel of heat is retarded and prevented between such parts of the construction. The inner end of portion 28 is separated from the edge of the rear side wall 2 by a strip of suitable insulating material 30 which retards and prevents the travel of heat from the portion 28 to the inner wall 2 of the structure. The end of member 28 which is disposed toward the front of the structure is angle-shaped so as to provide a shoulder or flange 31 behind 130

which the bolts 16 are adapted to lock. Flange or shoulder 31 is reenforced by the abutment thereagainst of insulation strip 29, jamb wall 3 and filling material 7. This 5 construction eliminates the necessity of providing the usual perforations for the bolts in the portion 28 of the jamb and permits a larger amount of filling material to be incorporated in the structure at this location 10 than is usually possible. On the inner end of bolt-receiving jamb portion 28 is a flange 32 which fits against the insulating strip 29 and which ends in an upset flange 33 projecting toward the front of the structure. 15 The end of flange 33 is adapted to be positively contacted by the insulating strip 18 provided on the inner face of the door and cooperates with such strip to form a seal which prevents the entry of heated air from 20 the joint between the jamb and door walls into the interior of the structure when the door is closed.

The lines of apertures on the jamb and door edge walls may be so arranged that 25 when the door is closed they will be in registration or not, as desired. Also, insulating material may be provided at any suitable point or points along either the jamb walls or the door edge walls. Such insulation may 30 conveniently take the form of strips of insulating material, such as rubber, asbestos, or the like, laced in and out through one or both the jamb wall and the door edge wall. 35 Such a line of lacing may be so arranged on one of the walls as to closely contact the wall of the other member when the door is closed, or a line of lacing may be provided in each of two registering lines of apertures, 40 one on the door and one on the jamb, so that when the door is closed, they will be brought tightly together, and will co-operate to form a seal which closes the joint between the jamb and the door walls and 45 which retards or prevents travel of heat through the joints. As shown in the drawings, a line of lacings 34, of asbestos or some other material, may be associated with the line of apertures 8 on the door, and a co- 50 acting lacing 35 of similar material may be associated with the line of apertures 20 on the jamb wall. When the door is closed these two lines of insulation are adapted to press tightly together, sealing the joint 36 between the walls 3 and 6, and co-operating 55 with the seal provided by flange 33 and insulation 18 to provide an intermediate, insulating dead air chamber 37.

In one possible modification of the construction above described, instead of making the jamb and door walls of the conventional step formation, they may be of serpentine or tortuous construction, as shown in Figs. 5 and 6, in order to present a longer 60 stretch of jamb and door walls which must

be traversed by heat before such heat reaches the interior of the structure. Such tortuous jamb and door wall construction may advantageously be combined with one or more lines of apertures or perforations in said 70 walls and with lacing of insulating material woven through such lines of perforations.

As shown in Fig. 5, the inner safe wall 2 is shown to extend to the outer surface of the structure, first forwardly along a straight 75 jamb portion 50, then rearwardly at an angle to portion 50, as at 51, creating a forwardly disposed projecting portion 52, then forwardly at an angle to portion 51, as at 53, and then forwardly, as at 54, to the front 80 of the safe. The door edge wall is formed to complementary shape, having a forwardly extending portion 55, then a rearwardly extending portion 56 creating a recess 57 adapted to receive projection 52 of the jamb 85 wall, and having a portion 58 which is complementary to jamb portion 53, and a portion 59 which is complementary to jamb portion 54. By this zig-zag or serpentine construction of the jamb and door walls the 90 length of the walls through which heat must travel to reach the interior of the cabinet from the outside is increased materially over the conventional stepped construction. In addition to this I preferably provide the 95 jamb and door walls with one or more series or lines of apertures, such as 60 and 61; also with one or more series or lines of sidewise extending radiating flanges 62 and 63, which extend into the filling material 7; and also 100 with lacing of insulating material, one, such as 64, on the jamb, and one, such as 65, on the door wall, adapted to register with each other and to coact to seal the joint 36 between the jamb and door walls. These apertures, radiating flanges, and lacings may be 105 similar in structure, in cooperation, and in function to the apertures, radiating flanges, and lacings referred to heretofore. By reason of the specific configuration of the 110 jamb and door edge walls expansion of said walls, under the influence of heat, will cause a tighter sealing of the joint. A sealing of the joint may also be effected by permitting jamb wall projection 52 to come into close 115 contact with the jamb of the recess 57 of the door wall. A seal at this location in combination with a seal effected by the lacings 64 and 65 will produce an insulating dead air chamber 66 between such seals, and 120 thus further enhance the resistance of the structure to penetration by heat.

The construction shown in Figs. 6 and 7 is somewhat similar to the construction shown in Fig. 5, in that both the jamb wall 125 67 and the door edge wall 68 are of tortuous or serpentine construction and jamb wall 67 having a projecting portion 69 fitting into a recess 70 on the door edge wall 68. As shown, however, the jamb wall is provided 130

with an outwardly opening, dovetailed recess 71 in which is located and secured a strip 72 of insulating material, such as rubber, asbestos, or the like. The door edge wall is 5 provided with a complementary, opposite dovetailed recess 73, opening inwardly, and which contains a strip 74 of similar insulating material. The construction is such that when the door is closed the exposed portions 10 of the insulating strips 72 and 74 are pressed tightly together, thus forming a tight sealing of the joint 36 between the jamb and door edge walls. The insulating strips 72 and 74 are preferably of resilient material 15 in order that the sealing of the joint may be insured at all times, and to eliminate the danger of the strips being warped or compressed out of shape permanently by continued operation of the door. In combination 20 with such construction, if desired, I may provide one or more series of lines of apertures, radiating flanges, and lacings of insulating material, such as have been described above. In this embodiment I find 25 it advantageous to provide a series of apertures 75 along the bottom walls of each of the recesses 71 and 73, and to provide radiating flanges 76 adjacent each of these lines of apertures and extended into the 30 filling material 7 contained in the structure. The apertures 75 and radiating flanges 76 are similar in construction, cooperation, and function to the apertures and flanges described heretofore.

35 Preferably each of the insulating strips 18, 29, 30, 72 and 74; also each line of apertures 8, 9, 20, 21, 60, 61 and 75; also each line of lacing 34, 35, 64 and 65; also each line of radiating flanges 19, 22, 62, 63 40 and 76; as well as jamb tongues 52 and 69, and cooperating door wall recesses 57 and 70 and jamb and door insulation holding recesses 71 and 73, extend continuously about the entire jamb and door, although, 45 obviously, any one or more of these various elements of the construction may be omitted, or be made non-continuous, or otherwise be modified without departing from the scope of this invention.

50 In my application Serial No. 651,467, filed on even date herewith, I have disclosed jamb and door walls comprising a plurality of separate portions and continuous heat radiating flanges extending sidewise from 55 said walls into the filling material. Reference to such application is hereby made.

From the foregoing it will be readily apparent that the travel of heat through the jamb walls of the construction illustrated 60 in Fig. 1 is retarded and prevented first, by line 20 of apertures; second, by line 21 of apertures; third, by insulating strip 29; then by insulating strip 30, and also by reason of the fact that baffle flanges 22 conduct, 65 radiate and diffuse heat travel along this wall into the filling 7, whereby said heat is absorbed. The travel of heat along the door edge walls 6 is retarded first, by line 8 of apertures; second, by line 9 of apertures; then by insulating strips 18, and also by heat radiating flanges 19 which conduct, radiate and diffuse heat from the wall 6 into filling material 7, whereby such heat is absorbed. The travel of heat through the joint between the walls 3 and 6 is prevented 70 by the seal provided by cooperating insulating lacings 34 and 35; by the seal provided by the coaction between the flanges 33 and insulating strip 18, and also by the insulating dead air chamber 37 provided between 75 said two seals. The travel of heat along a path or course behind the jamb wall 3 is retarded by radiating flanges 22 which absorb heat traveling through and along such path and which radiate and diffuse 80 such heat into the filling 7, and the travel of heat along a path or course behind the door edge wall 6 is prevented by radiating flanges 19, which function similarly to flanges 22, and which conduct and radiate 85 heat into filling material 7 of the door.

As above pointed out, the lines of apertures and the radiating flanges of the modifications shown in Figs. 5, 6, and 8 function 90 in a similar manner, and the lacings shown in Fig. 5 and the insulating strips shown in Fig. 6 serve to seal the joint between the jamb and door walls. The tortuous jamb and door wall construction serves to retard 95 the travel of heat directly through these walls, and also serves to radiate the heat into the filling material of the jamb and door, which material absorbs such heat and effects a cooling of the jamb and door walls.

As many changes could be made in the 100 above construction and as many apparently widely different embodiments of this invention could be made without departing from the scope thereof, it is intended that all matter contained in the above description or 105 shown in the accompanying drawings shall be interpreted as illustrative and not in a limiting sense.

What I claim is:—

1. In a structure of the character described, in combination, a transverse wall, and means for retarding heat travel through said wall, said means comprising a continuous line of apertures in said wall and heat radiating flanges extending from said wall. 110
2. In a structure of the character described, in combination, a transverse wall, and means for retarding heat travel through said wall, said means comprising a plurality of lines of apertures in said wall and a plurality of lines of heat radiating flanges extending from said wall. 115
3. In a structure of the character described, in combination, a transverse wall having means including a line of adjacent 120

apertures of substantial size whereby the heat conductivity of said wall is reduced a substantial amount, and heat insulating material seated in said apertures.

5 4. In a structure of the character described, in combination, a transverse wall having means including a line of apertures whereby the heat conductivity of said wall is reduced, heat insulating material seated 10 in said apertures, and heat radiating flanges extending sidewise from said wall.

5. In a structure of the character described, in combination, a jamb wall having means including a line of adjacent apertures 15 whereby the heat conductivity of said wall is reduced a substantial amount, a door edge wall having means including a line of adjacent apertures whereby the heat conductivity of said wall is reduced a substantial 20 amount, heat insulating material seated in the apertures of said jamb wall, and heat insulating material seated in the apertures of said door edge wall.

6. In a structure of the character described, in combination, a jamb wall having means including a line of adjacent apertures whereby the heat conductivity of said wall is reduced a substantial amount, a door edge wall having means including a 25 line of adjacent apertures whereby the heat conductivity of said wall is reduced a substantial amount, heat insulating material seated in the apertures of said jamb wall, and heat insulating material seated in the 30 apertures of said door edge wall, said insulating material on jamb and door edge walls being positioned to come together when said door edge wall is seated against said jamb wall.

40 7. In a structure of the character described, in combination, a transverse wall having means, including a line of apertures of substantial size and a flexible strip of fibrous insulating material laced in and out 45 through said line of apertures, whereby the heat conductivity of said wall is reduced.

8. In a structure of the character described, in combination, an inner wall, an outer jamb wall portion, and a separate, 50 intermediate, bolt-receiving jamb portion, said inner wall and intermediate portion being substantially out of direct contact with each other, and means for retarding heat travel through said outer jamb wall portion, 55 said means comprising a plurality of heat

radiating flanges extending from said outer jamb wall portion.

9. In a structure of the character described, in combination, an inner wall, an outer jamb wall portion, and a separate, 60 intermediate, bolt-receiving jamb portion, said inner wall and intermediate portion being substantially out of direct contact with each other, and means for retarding heat travel through said outer jamb wall portion, 65 said outer jamb wall portion having heat conductivity reducing apertures and heat radiating flanges.

10. In a structure of the character described, a jamb wall having at its inner end 70 a forwardly projecting flange, a door having an edge wall adapted to be seated against said jamb wall, and insulating material on said door positioned to come tightly against the forward end of said flange.

11. In a structure of the character described, a jamb wall having at its inner end a forwardly projecting flange, a door having an edge wall adapted to be seated against said jamb wall, and insulating material on said door positioned to come tightly against the forward end of said flange, 75 insulating material on said jamb and insulating material on said door edge walls, the insulating material on said jamb and door edge walls being positioned to come together when said door edge wall is closed against said jamb wall.

12. In a structure of the character described, in combination, an inner wall, an outer jamb wall portion, a separate, intermediate, bolt-receiving jamb portion, said inner wall and intermediate portion being substantially out of direct contact with each other, insulating material intermediate said 90 inner wall and intermediate portion, said intermediate portion and said outer jamb portion being substantially out of direct contact with each other, insulating material intermediate said intermediate portion and said outer portion, said intermediate jamb portion having at its inner end a forwardly projecting flange, a door having an edge wall adapted to be seated against said jamb wall, and insulating material on said door 100 positioned to come tightly against the forward end of said flange.

This specification signed this 2nd day of July, 1923.

DAVID H. BELLAMORE.
